RE37,110 E * 3/2001 Hollister 206/365

(75) Inventor: **Serge Courteix**, Dammartin en Goële (FR)

* cited by examiner

(73) Assignee: **Stelmi Trading International**, La Courneuve (FR)

(**) Term: **14 Years**

Primary Examiner—Ian Simmons
(74) Attorney, Agent, or Firm—Lawrence E. Apolzon; Fross Zelnick Lehrman & Zissu, P.C.

(21) Appl. No.: **29/120,234**

(57) **CLAIM**

(22) Filed: **Mar. 16, 2000**

The ornamental design for a needle protecting device, as shown and described.

(30) **Foreign Application Priority Data**

DESCRIPTION

Sep. 16, 1999 (FR) 99 5694

FIG. 1 is a bottom view of the device;

(51) LOC (7) Cl. **24-02**

FIG. 2 is a side view;

(52) U.S. Cl. **D24/130**

FIG. 3 is a top view; and,

(58) Field of Search D24/130; 206/363,

FIG. 4 is a perspective view.

206/364, 367; 604/192, 295, 263, 110,
54
